NIPPLE FOR CALF FEEDING BUCKETS

Murray J. McCrary, Weatherby, Mo.

Application April 27, 1950, Serial No. 158,438

1 Claim. (Cl. 119—71)

1 This invention relates to a calf feeding bucket, and more particularly to a bucket having a nipple secured to a lower side edge to facilitate the feeding of suckling calves.

The principal object of the present invention is to provide a feeding bucket having a nipple simulating as nearly as possible the condition of feeding a calf from a bucket as it would by nursing its mother as nature has provided. In practically every instance it is very difficult to teach a calf to drink from a bucket after it has been taken away from its mother and even after it has been taught to drink from a bucket it will usually drink so fast that the milk has an undesirable effect on the calf. The present invention is designed to overcome these undesirable results.

Other objects of the present invention are to provide a calf feeding bucket having an opening in the side wall near the bottom thereof adapted to receive a coupling device; to provide a ball valve in said coupling member; to provide the coupling member with an annular flange around the outer perimeter thereof; to provide a nipple having an annular flange on the inside near the open end thereof adapted to engage over the flange of said coupling member; to provide means for securing said coupling member in the opening in the bucket so that the end of the nipple will engage against the outer wall of the bucket to prevent leakage of milk from the bucket; to provide a valve constructed so that suction by the calf on the nipple will prevent an undue amount of milk from passing through the nipple; to provide a device of this character in which the nipple will stand the strain of pushing and pulling natural to the suckling calf and periodical lunging as is often the case with such calf satisfying its hunger; and to provide a device of this character, having few parts, simple, economical to manufacture and efficient in operation.

In accomplishing these and other objects of the present invention, I have provided improved details of structure the preferred forms of which are illustrated in the accompanying drawings, wherein:

Fig. 1 is a vertical cross section through the bucket showing the nipple attached to the side thereof near the bottom.

Fig. 2 is an enlarged longitudinal cross section through the nipple and coupling member shown attached to the bucket, but not in taut condition.

Fig. 3 is a longitudinal cross section through the nipple showing the coupling member and

2 nipple in assembled condition for retaining the nipple thereon.

Fig. 4 is a longitudinal cross sectional view of the nipple and coupling member shown attached to the bucket without a sealing washer.

Fig. 5 is a longitudinal cross section through the nipple shown attached to a bucket illustrating a modified form of the invention.

Referring more in detail to the drawing:

10 1 designates a bucket embodying the features of my invention having a side 2, bottom 3, and bail 4 attached to ears 5 as is the usual practice. Secured to the rear side of the bucket by welding or other visible means is a hook or strap 6 adapted to engage over a supporting member 7 to hold the bucket slightly at an angle to present the bucket to the calf in as nearly normal position as possible and so that if the calf should lunge at the bucket, there will be a spring or 20 resilient action to prevent spilling of the milk from the bucket. It is desirable to have the bucket attached considerably higher than the normal position of the calf's head in order that the calf will not be in such a position to incite butting or lunging at the bucket.

20 An opening 8 is provided in the front side of the bucket opposite the supporting bracket 6 near the bottom 3 thereof, and a tubular coupling member 9 is adapted to engage in said opening. The shank of the coupling member is threaded as indicated at 10 and the outer end thereof is enlarged providing an annular flange 11 and a shoulder 12 providing a throat or valve member 13 in the coupling member in which a ball or 30 outflow valve 14 is adapted to engage. The outer end of the tubular member is crimped or otherwise bent inwardly on its outer edges as indicated at 15 to retain the ball therein. The ball may be glass, metal or other suitable material.

30 The nipple or teat 16 has an open end adapted to engage over the coupling member on the outside of the bucket. Spaced a short distance from the open end of the nipple on the inside thereof is an internal annular flange or rib 17 and on the outside of the nipple substantially in alignment with the annular flange 17 is an annular groove 18. The outer open end of the nipple has an annular lip 19 slightly larger than the main body portion 16 of the nipple. The threaded shank portion of the coupling member extends through the opening 8 of the bucket and a threaded nut 20 is adapted to engage said threads to hold the coupling member shoulder and the rib in close contact. The nut 20 has a knurled edge as indicated at 21.

In assembling the device constructed as described, the open end of the nipple is placed over the valve end 22 of the coupling member 9 so that the annular flange 17 engages against the shoulder 23 formed by the annular flange 11 of the coupling member. The shank or threaded end of the coupling member is then inserted in the opening 8 of the bucket and the nut 20 engages on the threads 10 inside the bucket. Tightening of the nut 20 will cause the lip 19 to engage against the side wall of the bucket as indicated in Fig. 4 and continued tightening of the nut 20 will form a complete seal between the bucket and the nipple, the lip being pushed backwardly toward the body of the nipple and the annular groove 18 causing the inside annular flange 11 of the nipple to fit securely against the shoulder 23 to retain the nipple on the coupling member. The outer end of the nipple is provided with the usual opening 25 so that milk will flow therethrough from the bucket. In Figs. 2 and 3 a washer 26 made of pliable material may be inserted between the lip end 19 of the nipple and the wall of the bucket if desired.

In Fig. 2 the nipple is shown attached to the coupling member before the nut 20 is fully tightened. In Fig. 3 the nipple is shown after the nut has been tightened down which demonstrates the cooperation between the lip 19, the annular groove 18 and annular flange 17 on the inside of the nipple to hold the nipple securely against the shoulder 23 of the coupling member to retain the nipple thereon.

In Fig. 4 the coupling member is shown attached to the bucket without the washer 26, the lip 19 serving as a sealing means against the side of the bucket as above described.

When the calf is using the feeder as above described, it will take hold of the nipple 16 with its mouth and working of its jaws as nature has taught will cause a suction on the nipple and the ball 14 will move back and forth in the chamber 21 of the coupling member and such movement will limit flow of milk from the bucket through the throat 13 due to the air being pumped through the nipple by working thereof by the calf. Ordinarily the ball will remain seated so as to retain the milk in the bucket when the calf is not working the nipple.

In Fig. 5 I have illustrated a modified form of the invention wherein the threaded shank 28 of the coupling member 9 is provided with an integral flange 29 on its inner end adapted to engage against the inside of the bucket and the outer end or valve container compartment 30 is slightly smaller than the threaded shank portion 28 to allow a threaded nut 31 to be inserted over the valve portion 30 and engage the threads of the shank. The nut 31 forms an annular flange around the shank for engagement of the nipple thereover.

In assembling the device of this form of the invention, the valve container portion 30 and shank 28 is inserted through the opening in the wall of the bucket from the inside, the open end of the nipple is then inserted over the nut 31 until the internal annular flange 17 passes over

the nut and engages against the side face 32 thereof as illustrated in Fig. 5. The open end of the nipple and nut is then inserted over the valve container portion 30 and the nut engages the threaded shank 28 and turning of the nipple and nut will tighten the same on the shank until the lip 19 engages against the side wall of the bucket to obtain a seal of the nipple against the bucket. If desired the washer 26 may also be used between the bucket and lip. The valve arrangement in this form of the invention is the same as that shown in Figs. 1 to 4 inclusive, except that it will be obvious there need be no shoulder in the container portion indicated at 12 (Fig. 2), the throat 13 of the coupling member acting as a stop or shoulder against which the ball 14 will rest.

It will be obvious from the foregoing that I have provided an improved calf feeder bucket having a removable coupling member to facilitate assembly of the bucket and to provide a connection for the nipple which will tend to eliminate excessive wear and replacements when in use.

What I claim and desire to secure by Letters Patent is:

Apparatus for attaching a flexible nipple having an open end and provided with an internal annular rib adjacent said open end and forming an annular lip on the outer edge of the open end of the nipple to a feeding bucket having an opening in one side adjacent the bottom thereof comprising, a tubular coupling having a threaded portion at one end thereof which extends through the opening in the bucket, said coupling being elongated and having its end outside the bucket enlarged forming an annular flange portion providing a valve chamber in the coupling exteriorly of the bucket, an outflow valve in the chamber, said chamber being slightly larger than said threaded portion and said annular flange portion being reduced at the open end thereof for retaining the valve therein, said enlarged end removably receiving the flexible nipple sleeved thereon with the internal annular rib between the bucket wall and the annular shoulder and the lip engaging the outer wall of the bucket around said opening, and an internally threaded nut engaging the threaded portion of the coupling inside said bucket for retaining said coupling in said opening and drawing said lip against the wall of the bucket to form a seal around said opening in the bucket and exerting pressure on the annular rib to retain the nipple on the coupling.

MURRAY J. McCRARY.
